UNITED STATES PATENT OFFICE.

HENRY G. LEWIS AND WALTER S. MAYER, OF PHILADELPHIA, PENNSYLVANIA,
ASSIGNORS TO ELECTRIC SERVICE SUPPLIES COMPANY, A CORPORATION OF
PENNSYLVANIA.

ELECTRIC-LIGHTING MECHANISM.

1,426,490.

Specification of Letters Patent. Patented Aug. 22, 1922.

Application filed March 12, 1920. Serial No. 365,148.

To all whom it may concern:

Be it known that we, HENRY G. LEWIS and WALTER S. MAYER, citizens of the United States, and residents of Philadelphia, in the county of Philadelphia and State of Pennsylvania, have invented certain Improvements in Electric-Lighting Mechanisms, of which the following is a specification.

- 10 This invention is designed especially to provide simple and efficient means for automatically closing a lamp circuit that has been broken by the failure of a lamp as by the rupture of its filament or its imperfect contact, and it is adapted particularly for use in a lighting system, containing lamps connected in series, to maintain the normal operations of the remaining lamps in case one or more of such lamps should be broken.
- 20 In car lighting, as a leading application of the invention, the highest economy and efficiency are attained by the arrangement of lamps, including headlights, in series, with the usual disadvantage that the failure 25 of a single lamp breaks the circuit through other lamps with the loss of their lights.

It is an object of our invention to provide a car lighting system with means for maintaining lamps connected in series at normal 30 brilliancy notwithstanding the failure of one or more of such lamps.

In the practice of our invention, in its preferred form, we provide a fixture containing an electromagnet or solenoid coil in 35 circuit with each lamp of a series, in combination with conductors automatically connected by the electromagnet armature to close an auxiliary circuit around the lamp upon the rupture of the circuit through the 40 lamp and the consequent deenergizing of the electro-magnet; the auxiliary circuit being provided with resistance equal to that through the lamp to maintain the remaining lamps at normal brilliancy.

45 In the accompanying drawings, Fig. 1 is a sectional elevation of a lamp fixture made in accordance with our invention; Fig. 2 is a sectional view of details of the same; Fig. 3 is a plan view taken on the line 3^x-3^x of 50 Fig. 1, and Fig. 4 is a diagrammatic view of a car lighting system in which our improvements are adapted for use.

The mechanism, as illustrated in the drawings, comprises the insulating base 1 adapted 55 to be secured to a support 2, as a car roof,

and a spider or skeleton frame 3 fixed to the base. A holder 4, for the lamp socket 5, has a top plate 4^a fixed to the ring 3^a of the frame 3 and a flared mouth 4^b for engaging the lamp shade 6 which is supported by the 60 holder.

The base 1 is provided with the insulating projections 1^a, 1^b and 1^c for supporting respectively the conducting clips 7 and 7^a, 8 and 8^a and 9, and brackets 10, 11 and 12 65 fixed to the base carry the respective resistance tubes 13, 14 and 15. The resistance tube 13 has its opposite ends connected by the conductors 16 and 17 with respective clips 7 and 8; the resistance 14 has its respective 70 ends connected by the conductors 18 and 19 with respective clips 8^a and 9, and the resistance 15 has its respective ends connected by the conductors 20 and 21 with the respective clips 9 and 7^a. The clip 7 connects the 75 line wire or conductor 22 with the conductor 23 which is connected through the electromagnet coil 24 (engaged to the base by a U-shaped bearing 24') with the clip 25 fixed to the base 1 and connected by the conductor 80 26 with the lamp socket contact 5^a. The clip 7^a connects the line wire or conductor 27 with the conductor 28 which is in circuit with the shell 5^b of the lamp socket, the parts 5^a and 5^b being electrically connected through 85 the lamp 29.

Contacts 30 and 30^a are electrically connected with the respective clips 8 and 8^a and are adapted to be electrically connected and disconnected by the armature 24^a of the coil 90 24, the armature being provided with the cross piece or disk 24^b adapted to simultaneously engage both the contacts 30 and 30^a by the fall of the armature by gravity and the action of the spring 31 when the electromagnet is deenergized.

An ornamental open guard or metal basket 95 32 passes over the holder 4 and is fixed to the base 1, concentric with the ring 3^a.

Assume the lamps 29 connected in series 100 in the circuit 33 connecting the trolley wire 34 with the ground and that one of these lamps should break or fail to close its circuit. Then the corresponding coil 24 is deenergized and the current (which flows 105 through the conductors 22, 7, 23, 25, 26, 5^a, 29, 5^b, 28, 7^a and 27 when the corresponding lamp 29 functions) now flows through the conductors 22, 7, 16, 13, 17, 8, 30, 24^b, 30^a, 8^a, 18, 14, 19, 9, 20, 15, 21, 7^a and 27 of 110

equivalent resistance to the broken lamp circuit thus maintaining the current through the remaining lamps which burn at normal brilliancy.

5 Having described our invention, we claim:

1. In an electric lighting mechanism, the combination of an insulating base provided with a pair of insulating projections, a lamp 10 socket holder, a skeleton frame for fixing said holder to said base, a lamp socket carried by said holder, an electro-magnetic coil fixed to said base, an armature for said coil, a pair of conducting devices fixed to one of 15 said projections, conductors connecting said devices through said socket and coil, a pair of conducting devices fixed to the other of said projections and adapted to be connected by said armature, and conductors for connecting said devices serially through said armature in parallel relation with said coil and socket.

2. In an electric lighting mechanism, the combination of an insulating base, a lamp 25 socket, means for fixing said socket to said base, a substantially U-shaped device fixed to said base, an electro-magnetic coil carried

by said device, an armature for said coil, angular supports fixed to said base, resistance tubes respectively fixed between angular supports aforesaid, a pair of conducting devices fixed to said base, a pair of contacts fixed to said base, said armature adapted for connecting said contacts, conductors connecting said devices through said socket and coil 35 and conductors connecting said devices through said tubes, contacts and armatures around said coil and socket.

3. In an electric lighting mechanism, the combination with an insulating base, a lamp 40 socket fixed to said base, and a circuit comprising terminals of said socket and an electro-magnetic coil fixed to said base, said coil having an armature freely suspended therein, of an auxiliary circuit around said 45 coil, said auxiliary circuit comprising contacts fixed to said base and adapted to be connected by said armature when said coil is deenergized.

In testimony whereof we have hereunto 50 set our names this 10th day of March, 1920.

HENRY G. LEWIS.
WALTER S. MAYER.
